UNITED STATES PATENT OFFICE.

JOHN BETJEMANN, OF 36 AND 38 PENTONVILLE ROAD, ENGLAND.

LOCK.

SPECIFICATION forming part of Letters Patent No. 224,380, dated February 10, 1880.

Application filed November 18, 1879. Patented in England, July 31, 1879.

To all whom it may concern:

Be it known that I, JOHN BETJEMANN, of the firm of George Betjemann & Sons, of 36 and 38 Pentonville Road, in the county of Middlesex, England, have invented new and useful Improvements in Locks for various purposes, but more especially adapted for use with cigar-boxes, which improvements are fully set forth in the following specification, and for which provisional protection has been granted to me on an application for patent in England, dated July 31, 1879, No. 3,106.

The invention has for its object improvements in locks for various purposes, but more especially adapted for use with cigar-boxes. For this purpose I dispense with the ordinary link-plate or hasp and form the lock entirely self-contained.

In lieu of the aforesaid link-plate or hasp, I hinge or otherwise articulate to the lock a flap capable of being turned up in a line with the face of the lock, or thereabout, and also of being turned down at a right or other required angle. The lock is fixed on the outside of the box or other article to which it is applied, and, when required to be fixed temporarily to a cigar or other box, I, according to one arrangement, fix to the back of the lock one or more pointed screwed studs to which fly-nuts are applied, and when only one such screwed stud is employed I fix also a steady-pin to the back of the said lock. I force the screwed stud or studs through the material of the cigar or other box and apply a fly-nut thereto on the inside of the box, so as to fix the lock securely thereto.

According to another arrangement I employ only one stud on the back of the lock, and form it as a wood-screw, to enable the lock to be fixed in position by screwing such wood-screw into the front of the box. Then, by turning the flap over the top or lid of the box and by the shooting of the bolt either by a spring or key, the flap, by one or more catches attached thereto, is locked in position over the lid, whereby the latter is securely fastened down, and cannot be opened except by the use of the proper key.

The interior construction of the lock may be of any ordinary or convenient description, but forms no part of my present invention.

And in order that my said invention may be

more clearly understood and readily carried into effect, I will proceed, aided by the accompanying drawings, more fully to describe the same.

Referring to the drawings, Figure 1 is a perspective view of a cigar-box with a lock applied thereto constructed according to my invention, and showing the lid of the cigar-box fastened down by the lock; and Fig. 2 is a section of the same. Fig. 3 is a back view. Fig. 4 is a plan, and Fig. 5 is an end, view of the lock separately, showing the flap unlocked and turned back.

In the figures above referred to the lock is represented as being provided at the back thereof with a wood-screw for fixing it in position; but at Fig. 6 I have shown a section of a cigar-box with my improved lock applied thereto, in which the said lock is fixed in position by means of a fly-nut acting in combination with a screwed stud.

According to my invention I dispense with the ordinary separate link-plate or hasp and form the lock entirely self-contained.

In lieu of the aforesaid link-plate or hasp, I hinge or otherwise articulate to the lock *a* a flap, *b*, capable of being turned up in a line with the face of the lock *a*, or beyond, as represented at Figs. 3, 4, 5, and also of being turned down at right angles to the face of the lock, as represented at Figs. 1, 2.

The lock *a* is fixed on the outside of the box or other article to which it is applied, and, when required to be fixed temporarily to a cigar or other box, I, according to the arrangement represented at Fig. 6, fix to the back of the lock one or more pointed screwed studs, *c*, and when only one screwed stud *c* is employed, as shown, I sometimes fix one or two steady-pins, *d*, to the back of the said lock.

In applying the arrangement represented at Fig. 6 to a cigar-box I force the screwed stud or studs through the material of the cigar or other box and apply a fly-nut, *e*, thereto on the inside of the box, so as to fix the lock securely in position; or, according to the arrangement represented at Figs. 1, 2, 3, 4, 5, I dispense with the steady-pins *d* and make the screwed stud *c* into the form of a wood-screw, which I simply screw into the front of the box to which the lock is to be applied.

The flap *b* has fixed thereto a hasp or catch,

b', to act in combination with the bolt of the lock, and such hasp or catch *b'*, as also the bolt, is, by preference, suitably beveled, as shown at Figs. 3, 4, 5, to enable the same to be used as a snap-fastening, while a key is employed to unlock the same when required.

By turning the flap *b* over the top or lid of the box, and by the shooting of the bolt either by a spring or key, the flap is locked in position over the lid, whereby the latter is securely fastened down, and cannot be opened except by the use of the proper key.

The interior construction of the lock may be of any ordinary or convenient description, but forms no part of my present invention.

The lock may be fixed to the article to which it is applied in other manner than those above described.

Having thus described the nature of my said invention and the mode in which I carry the

same into effect, I would have it understood that what I claim is—

1. The combination, with a lock, of the hinged flap *b*, secured to the front plate of said lock so as to overlap the box-cover, and having a catch or hasp, *b'*, as and for the purpose set forth.

2. As a new article of manufacture, a locking device consisting of lock *a*, having on its rear plate screw stud or studs *c*, and a locking-flap, *b*, hinged to the front plate of said lock so as to overlap the box-cover, and having a hasp or catch, *b'*, as and for the purpose set forth.

JOHN BETJEMANN.
